FRANK W. CHERRINGTON, OF TOLEDO, OHIO

METHOD OF DRYING OR TREATING TIMBER AND THE LIKE

Continuation of application Serial No. 681,295, filed December 17, 1923. This application filed June 14, 1928. Serial No. 285,466.

This invention relates to a method of drying or treating timber or similar material having cells or ducts which are arranged in more or less parallel relation and, in a piece 5 of timber, correspond to the grain of the wood which extends from one end thereof to the other.

The present application is a continuation of my earlier application filed December 17, 10 1923, Serial No. 681,295.

It is a fact that, prior to my invention, no method had been known by means of which wood or timber could be economically and speedily dried. Nature's own method of drying, employing the elements of time and air, is still in extensive use. Kiln dried lumber constitutes only a small proportion of the total amount of lumber used and is limited to a thickness of not more than four inches. 15 It takes several weeks for proper kiln drying, while the present method takes only a few hours. Air dried lumber is stronger, more durable and more economical for use in scores of important industries, among which may be 20 mentioned the railroads and the manufacturers of automobiles and various implements.

In nature's method of air seasoning, considered to be the best, the green timbers are 25 stacked in such a manner as to allow free circulation of air on all sides. The air, which is drier than the green timbers, absorbs moisture from the surface fibres of the wood. As the surface dries, capillarity draws moisture 30 from the interior of the wood to the surface and this flow of moisture is mainly toward the ends of the timber. The moisture content in green timber is about 60%, most of which is free sap and water contained in the 35 wood cells or ducts. This free sap and water naturally are the first to be expelled by capillarity and then comes the slower expulsion of the water and sap actually within the wood cells. As these wood cells lose their moisture, they dry and harden, and this gives 40 the seasoned wood its strength. The object of my invention is to provide a method of drying which follows nature's method as closely as possible, except as to the time required, 45 which is reduced to a minimum. It is easily

demonstrated that, if the wood is rotated, with its cellular structure or sap ducts parallel to the resultant centrifugal force, that is, radial to the axis of rotation, the capillary action forcing the water and sap to the surface will be accelerated in proportion to the speed of rotation and the distance from the axis of rotation. If dry air is admitted through the top of a closed container, within which green timbers are rotated in this 55 manner, it will become saturated with moisture expelled from the ends, and will gravitate toward the bottom of the container, where it may be withdrawn.

It is upon these physical principles that 60 my invention is based. Thus a speedy, harmless, and economical means of extracting the moisture from green timbers is provided.

In order that my invention may be fully understood, I have illustrated, in the accompanying drawings, apparatus by means of which the method may be carried out.

In the drawings:

Figure 1 is a side elevation of one type of apparatus.

Fig. 2 is a plan view of another type of apparatus, including a container which is shown in section.

Fig. 3 is a detail view of a timber or tie holder, which may be used in connection with 70 the apparatus.

Fig. 4 is an end elevation of a tie in a holder.

According to Figure 1, the apparatus is driven by a motor 1 having a shaft 2 which carries a bevel pinion 3 in mesh with a bevel gear 4 secured to the upper end of a vertical shaft 5. The motor 1 is mounted on a platform 6, on which is a counterbalance 7. The apparatus is supported by bearings 8 in a member 9, which in turn is supported by bearings 10 in a fixed overhead frame 11, supported by uprights 12 forming a base 13. The shaft 5, thus suspended, may be rotated at a high speed. A series of spiders are secured to the shaft 5, and secured to each spider are 85 a series of radially extending pockets 14, each adapted to receive a railroad tie 15, or other piece of timber for which the apparatus is adapted. Each pocket 14 may be suitably constructed to clamp or otherwise retain the 90

100

timber 15, and a bolt 16, or other means engaging the outer end of the timber prevents the latter from being thrown outwardly by the centrifugal force developed by the rapid 5 rotation of the same about its axis.

5 In the form shown in Fig. 2, the motor 17 has a shaft 18 connected by a suitable coupling 19 to a main drive shaft 20, on which gears 21 are mounted. These gears may be 10 selectively connected to the shaft 20 by clutches 22, which are controlled from an operator's station by levers 23. Each gear 21 is in mesh with a gear 24 secured to a shaft section 25 mounted in bearings 26. The shaft 15 sections 25 are in alignment with each other and each carries a series of pockets 14 like those secured to the shaft 5 in Fig. 1. The rotating frame may be enclosed in a chamber 27, which may be provided with doors 28 for 20 inserting or removing the timber. Dry air, steam or impregnating liquid may be supplied to the chamber through a pipe 29, controlled by a valve 30. The impregnating liquid may be drawn off or the chamber exhausted through a pipe 31, controlled by a valve 32.

In drying and treating railroad ties according to my improved method, the rotatable frame is loaded with green ties, which are 30 securely anchored in the pockets 14 so that they may be rotated at a speed as high as fifteen hundred revolutions per minute. The rotating frame is preferably arranged to rotate about the vertical axis, and since considerable air circulation is generated by the rotation, there is less resistance and consequently less consumption of power, if the rotating frame is enclosed within a chamber.

All of the pockets 14 extend radially from 40 the axis of rotation, their inner ends being far enough from the axis to accommodate the desired number. As the timbers are thus held and rotated, the centrifugal force developed will act continuously in one direction 45 lengthwise of each duct, from one end thereof to the other and the rotation is rapid enough to cause a continuous flow of moisture from the outer ends of the timbers until they are thoroughly dried.

50 After the ties have been rotated until they are thoroughly air dried, any known process of treating them with creosote oil or the like, may be used without removing the ties from the chamber. When the ties have been thoroughly treated with creosote oil, they may be again rotated until all surplus creosote is removed, so that there is a maximum penetration of preservative with a minimum quantity of creosote oil. Surplus creosote thus 60 recovered may be gaged and the final minimum amount per cubic foot injected may be calculated. The ties will be dry and easy to handle after this final whirling has been completed. The rotating frames may, of course, 65 be arranged independently of the chamber,

so that one frame may be loaded while the previous load is being dried or treated. One chamber may be used for drying and another chamber for treatment. The loaded frames may be transferred to or from the chambers by an overhead crane or other suitable means. 70

My method of seasoning and treating timber has many advantages over the natural method which is most commonly used. It eliminates acres of storage yards, tracks and equipment. It makes it unnecessary to store millions of ties for many months while they are being seasoned, and thus releases millions of dollars of capital, with consequent saving in interest, depreciation, insurance and handling. It eliminates a great deal of expensive equipment now employed in treating timber. An absolute minimum of oil is used to secure maximum penetration. The ties, after being treated, are quite dry and easily handled. 75

It should also be noted that, in the natural drying of timber, the sap and moisture are conveyed to the surface of the timber only by capillary action. This process is necessarily slow, with the result that the cell or duct walls dry more rapidly at the surface than in the interior of the timber, causing shrinkage or collapse of the cell walls and consequent checking or cracking at the ends. In the treatment of the timber according to my method, the moisture which is discharged from the ends of the timber is rapidly replaced by moisture which is forced outwardly from the interior of the timber. This flow takes place at such speed that there is substantially no drying or hardening of the duct walls at the end of the timber. A rapid and uniform seasoning of the timber throughout its entire length is thus effected and there is substantially no checking or cracking. This 90 makes it unnecessary to use S or Z irons at the ends of the timber, as are necessary with timber dried by other methods. 95

100 While I have illustrated apparatus which may be used in carrying out my method, it is, of course, to be understood that this is only for the purpose of illustration and is not to be regarded as in any way limiting the scope of the invention as claimed. 105

110 What I claim is:

115 1. The herein-described method of treating or drying timbers or other like materials, which resides in rotating the material so as to cause progressive movement of the duct contents thereof from one end to the opposite end of the ducts and outwardly of the axis of rotation. 120

125 2. The herein-described method of treating or drying timbers or other like materials, which resides in rotating the material with the latter disposed radially of the axis of rotation so as to cause progressive movement of the duct contents thereof by centrifugal action from the inner to the outer end of the ducts and outwardly of the axis of rotation. 130

3. The herein-described method of treating or drying timbers or the like which resides in subjecting the duct contents to centrifugal force directed in such a manner as to cause progressive movement of the duct contents from one to the other end of the ducts to finally expel the contents through the latter of said ends of the ducts.

4. The herein-described method of treating or drying timbers or the like which resides in 10 subjecting the duct contents in the presence of a heated drying fluid or drier to centrifugal force directed in such a manner as to cause progressive movement of the duct contents from one to the other end of the ducts to finally expel the contents through the latter of said ends of the ducts.

5. The herein-described method of treating or drying timbers or the like which resides in 20 subjecting the duct contents to centrifugal force acting along the length of the ducts from one end to the other.

6. The method of treating or drying material having ducts therein, which consists in 25 rotating the material about an axis while said material is held in such a position with respect to said axis that centrifugal force acts lengthwise of each duct from one end to the other.

30 7. The method of treating or drying material having ducts therein, which consists in so arranging and holding the material with reference to an axis that each duct, substantially from one end of said duct to the other, 35 extends away from the axis, and rotating the material, while it is so held, about said axis.

8. The method of treating timber which 40 consists in arranging and holding several pieces in such a position that the sap ducts are in substantially radial relation to a common axis, and rotating the same, while so held, about said axis, whereby the centrifugal force thus developed tends to drive the contents of each duct continuously from one end 45 of the duct to the other.

In testimony whereof, I have hereunto signed my name to this specification.

FRANK W. CERRINGTON.
